UNITED STATES PATENT OFFICE.

MARTIN L. SENDERLING, OF JERSEY CITY, NEW JERSEY.

EXPANSION-LIFT.

1,080,375.

Specification of Letters Patent.

Patented Dec. 2, 1913.

Application filed December 30, 1911. Serial No. 668,697.

To all whom it may concern:

Be it known that I, MARTIN L. SENDERLING, a citizen of the United States, and a resident of Jersey City, in the county of 5 Hudson and State of New Jersey, have invented a new and Improved Expansion-Lift, of which the following is a full, clear, and exact description.

Among the principal objects which the 10 present invention has in view are: to provide a lifting mechanism having a pivoted base to permit a lateral swing of said mechanism thereon; to provide a thrust member for said mechanism, pivotally mounted 15 thereon to rock in a plane perpendicular to the plane of rotation of said base; and to provide a lifting mechanism having terminal thrust members and an intermediate flexible expansion member to separate said 20 thrust members, and pivotally connected with said thrust members to permit the disposition thereof in angularly-disposed planes.

One embodiment of the present invention is shown in the accompanying drawings, in which—

Figure 1 is a side elevation of a lift constructed and arranged in accordance with the present invention; Fig. 2 is a horizontal section taken on the line 2—2 in Fig. 1; Fig. 3 is a sectional elevation of a bottom fragment of the mechanism shown in Fig. 1, the link members thereof being shown in expanded arrangement, and the base and 35 operating screw being broken and contracted; Fig. 4 is a horizontal section of the toggle levers taken on the staggered line 4—4 in Fig. 1; Fig. 5 is a vertical section taken on the line 5—5 in Fig. 1; Fig. 6 is a vertical section taken on the line 6—6 in Fig. 40 3; Fig. 7 is a detail view of an upper fragment of the expansion member, showing in dotted lines the angular disposition of the thrust platforms; Fig. 8 is a vertical section taken on the line 8—8 in Fig. 9; Fig. 9 is a view of an upper or outer end fragment 45 of a lift constructed in accordance with a modified form of the present invention; Fig. 10 is a modified form of the construction for the joints of the couples, shown in longitudinal section.

As seen in the accompanying drawings, the lift is provided with a base plate 11.

At both ends of the base plate 11 are standards 12, to form bearings for the ends of a 55 screw-threaded shaft 13. The shaft 13 has ends reduced to form journals to rest in the bearings on the standards 12 and below bearing caps 14. The reduced ends 19 of the standards 12 and the caps 14 form bearings for the bracket ends 15 of a pivot bar 16, to permit said bar and structure supported thereby to swing independently of the shaft 13. The bar 16 is T-shaped in cross section, having a centrally-disposed 60 pendent flange 17. The flat top of the bar 16 forms a runway for the base plate 20 which is directly connected with the pivot blocks 18, as seen best in Fig. 4 of the drawings.

The base plate 20 is provided with downwardly-extending flanges 21, which flanges infold the bar 16. The base plate 20 is separable from the pivot blocks 18, so that said blocks may be placed in position from above, 75 so that grooves formed vertically therein may register with guide flanges 22 with which the nuts 23 are furnished. The nuts 23 above referred to are provided with threads to register with the threads of the 80 screw shaft 13. The threads of said shaft, at opposite ends thereof, are relatively reversed; that is to say, the threads have a right- and left-handed pitch, meeting at the center of the shaft midway between the 85 standards 12. The nuts 23 are disposed equi-distant from the middle of the shaft, and when so disposed, receive the blocks 18, to be thereafter held thereby from rotation.

The shaft 13 is rotated by any suitable 90 means, that shown in the drawings consisting of the crank handle 24. (See Fig. 3 of the drawings). By rotating the shaft in one direction, the nuts 23 and pivot blocks connected therewith will move toward the 95 center, and when rotating in the reverse direction, said nuts and pivot blocks will move from said center. The pivot blocks 18 are both provided with trunnions 25. The trunnions 25 form bearings for the ends of levers 26, 27 and 28 and an auxiliary lever 29. The auxiliary lever 29 is paired with the central lever 28 in the first or bottom couple of the expandible structure or lazy-tongs, and is not repeated in the superposed 105 couples.

In Fig. 2 of the drawings is shown the relative disposition of the levers 26, 27 and 28 and auxiliary lever 29. In Fig. 4 of the drawings is shown the relative arrangement of levers 30, 31 and 32. By the employment of the auxiliary lever 29, the structure is materially reinforced at the point where the initial force is applied to open the couples forming the lazy-tongs hereinafter described. Said auxiliary lever is a straight bar having perforations formed therein to form bearings upon one of the trunnions 25 as well as the connecting pins 33, 34 and 35. The main portion of the lever 28, as shown in Fig. 2, is disposed centrally between the levers 26 and 27, and in a plane coincident with the center of the shaft 13. To accommodate this disposition of the lever 28, it is provided with an elongated hub 36, which is perforated to receive the pin 33, to be thereby operatively connected with the auxiliary lever 29. The hub 36 is provided with a relatively short arm 37, the opposite end whereof is perforated to receive the trunnion 25 on the block 18. The length of the hub 36 is regulated to accommodate the separation or disposition of the trunnions 25. The lever 28 is suitably provided with a hub 38 to receive on the median plane of the lazy-tongs the pin 34, and at the end of the lever the pin 35. The hub 38 through which the pin 34 passes forms a spacing member for the levers 26 and 27. The levers 26 and 27 are provided with perforated hubs 39 and 40, respectively, through which a pivot pin 41 extends. The hubs 39 and 40 are provided with short arms 42, the ends whereof are perforated to receive the trunnions 25 of the block 18 adjacent thereto. The levers 26 and 27, at their upper or outer ends, are perforated to receive a pivot pin 43. The pivot pin 43 extends through perforations in a hub 44 on the lever 32 of the first of the superposed couples of the lazy-tongs. The hub 38, at the end of the lever 28, is perforated to receive the pin 35. The pin 35 passes through, and forms the pivot for, the auxiliary lever 29 and the levers 30 and 31 of the first of the superposed couples of the lazy-tongs. Each of the succeeding couples going to make up the lazy-tongs shown in Fig. 1 of the drawings consists of a lever 32 having a hub 44 at the lower end, a hub 45 at the upper end, and an intermediate hub 46 centrally located between the hubs 44 and 45. The hubs are connected by the levers 30 and 31 in the manner illustrated, and progressively; that is to say, each pair of levers 30 and 31 is connected with a hub 45 on a lever 32 by means of the pins 62 of the couple next below said pair of levers, and is connected with the hub 46 of the lever 32 corresponding in the couple with said levers 30 and 31, and with the hub 44 of the lever 32 next above said couple.

Each of the levers 32 is connected in the same progressive manner with, first, the upper ends of the levers 30 and 31 of the adjacent lower couple, with the levers 30 and 31 of the same couple at the median portion thereof, and with the levers 30 and 31 of the next succeeding upper couple, it being understood that each couple consists of the paired outside levers 30, 31 and the corresponding inside lever 32, the same being connected at their respective centers by the pivot pin 47. As many of the couples above described as is deemed necessary are in this manner united. At the upper end of the couple pile, a platform or head 48 is connected by means of outside levers 49 and an inside lever 50 to the upper couple of the above-described pile, by means of pivot pins 51, which extend through pivot lugs 52 extended from the under side of and at the end of the platform or head 48.

It will be noted by reference to Figs. 1 and 7 of the drawings that the levers 49 and the lever 50 are not centrally connected. By this arrangement, the platform is permitted to rock or be inclined relative to the vertical center of the lazy-tongs, as shown by the dotted lines in Fig. 7 of the drawings.

In the modified form of the invention, as shown in Figs. 8 and 9, the platform 48 is substituted by the thrust head 53, which is pivotally connected by the pivot bolt 54, to a yoke swing-head 55. The swing-head 55 is provided with perforated extensions 56, through which a pivot bolt 57 is passed. The bolt 57 also passes through perforations formed in the ends of outside links 58 and an inside link 59, the links 58 corresponding in superposed relation to the levers 30 and 31, and the link 59 corresponding in similar relation to the lever 32. By employing the pivot bolt 57, the head 53 is permitted to swing lengthwise of the couples of the lazy-tongs, and by employing the bolt 54, the head 53 may swing transverse said couples, forming thereby a universal joint for the head 53 with the lazy-tongs, to accommodate in disposition or tilt the object being moved by the herein-described lift.

From the foregoing, it will be understood that as the shaft 13 is rotated to cause the nuts 23 to move toward the center of said shaft, the levers 26 and 27 on the one side of the pin 34 are uplifted, using said pin as a fulcrum, and lifting the weight carried at the outer end of said levers by the pin 43. Correspondingly, the levers 28 and 29, operating through the pin 35 at the outer end thereof, lift the weight as represented by the levers 30 and 31 of the next succeeding superposed couple of the lazy-tongs. Correspondingly and coördinately, the various paired levers 30 and 31 and the various single levers 32 operate to pivot on the pins 47, to open upward, permitting

the outer ends of each couple to swing inward to a relatively narrowed position, as shown in Fig. 3 of the drawings, wherein it will be understood, the lazy-tongs are extended to approximate one-half the multiplied lengths of the various couples. It will also be seen that during this operation, the platform 48 or head 53, as the case may be, is permitted to swing to accommodate the position of the object being operated upon or lifted. By reversing the shaft 13, the nuts 23 and parts connected therewith are spread, with the result that the various couples are laterally expanded to draw them together vertically, operating to produce the result of lowering said platform or head and the load carried thereby.

In the normal position of the couples constituting the present lift, they are vertically nested, as seen in Fig. 1 of the drawings. In this position, the pivot blocks 18 are separated to the limit of their outward stroke, and if not otherwise protected, the threads of the shaft 13 would be exposed for accumulation of dust or grit, which subsequently would grind and cut said threads of the shaft 13 and those of the nuts 23. It is to avoid this that I have provided the covering tube 60. The tube 60 may be constructed of any suitable material, and is secured to the pivot blocks 18.

To avoid the collapsing of the tube 60 to clog the threads of the shaft 13, I provide a spiral spring 61, as seen best in Fig. 1 of the drawings where the tube is partly cut away to expose the same. The spring 61 is preferably constructed with as few as practical convolutions or turns, in order that the same may not form an obstruction for the juxtaposition of the pivot blocks 18 when moved to the center of the shaft 13, as seen in Fig. 3 of the drawings. In the position shown in Fig. 3 of the drawings, it will be noted that the tube 60 is compressed by the blocks 18 and the nuts 23 contained therein.

In the modified form of the construction shown in Fig. 10, provision is made for varying the separation between the levers 30 and 31 with greater facility than would be permitted by the employment of the hubs 44 and 45 permanently mounted upon the lever 32. In the form of the construction shown in Fig. 10, the lever 63 is not provided with a hub such as 45, but is perforated to pass a bolt 64. The bolt 64 is provided with nuts 65, the flanges of which bear against the ends of thimbles 66 and the sides of the levers 30 and 31, to compress the same toward the lever 63. The intervening space between the sides of each of the levers 63 and the connected levers 30 and 31, is regulated by the length of the sleeves 67.

It is obvious that when the above-described construction is employed, the trans-

verse dimension of the lazy-tongs may be infinitely varied.

Having thus described my invention, I claim as new and desire to secure by Letters Patent:

1. An expansion lift, comprising a screw-threaded shaft, a pair of nuts spaced apart on said shaft and in screw-threaded engagement therewith, a pair of upwardly- and inwardly-extending links carried by each of said nuts, one on each transversely opposite side thereof, and a bolt connecting the outside link fastened to one nut with the outside link fastened to the other nut, at a point substantially intermediate the length of said links, the upper end of one of the pair of links having a pair of links pivoted thereto, the free end of the other pair of links having a single link pivoted thereto and positioned between said last-mentioned pair of links. 70

2. In an expansion lift, a toggle joint, comprising two parallel links, a single link pivotally connected to the ends of said first-mentioned links and positioned in a plane 90 extending between the same, and a second pair of links pivoted on opposite sides of the free end of said single link.

3. An expansion lift, comprising a screw-threaded shaft, means supporting said shaft at opposite ends thereof, a track supported by said means, adjacent its opposite ends, a nut in threaded engagement with said shaft, a housing carrying said nut, means permitting a vertical movement of said housing relative to said nut, and a sliding connection between said housing and said track. 95

4. In an expansion lift, a screw-threaded shaft, a toggle joint carried by said shaft, 105 so that the rotation of the same will actuate said toggle joint, a supporting platform carried by said toggle, and a connection between said toggle and said platform, permitting said platform to assume an angular position with reference to the line of movement of said toggle. 110

5. In combination with a threaded shaft, nuts carried by said shaft, a toggle carried by said nuts, a housing for said nuts, and a track supporting said housing, said track rotatably mounted relative to said shaft. 115

6. In combination with a toggle, a supporting platform, and a link connection between said toggle and said platform, permitting said platform to swing in two directions at right angles to each other. 120

7. In combination with a shaft having a set of right-hand and a set of left-hand threads thereon, a nut in engagement with each of said sets of threads, a covering inclosing said shaft between said nuts, and means maintaining said covering spaced from said shaft. 125

8. In an expansion lift, a toggle having 130

three links spaced apart transversely, two of said links being connected.

9. In combination, a screw-threaded shaft, nuts mounted on said shaft, a toggle connected with and actuated by said nuts, and a support for said nuts adapted to take the weight of said toggle off said shaft.

In testimony whereof I have signed my name to this specification in the presence of two subscribing witnesses.

MARTIN L. SENDERLING.
